UNITED STATES PATENT OFFICE.

THOMAS A. WATSON, OF HOUSTON, TEXAS.

MOSQUITO-NET FRAME.

SPECIFICATION forming part of Letters Patent No. 325,464, dated September 1, 1885.

Application filed June 23, 1883. Renewed June 9, 1885. (No model.)

To all whom it may concern:

Be it known that I, THOMAS A. WATSON, of Houston, Harris county, Texas, have invented a new and Improved Folding Mosquito-Net Frame, of which the following is a full, clear, and exact description.

This invention consists of an arm pivoted to a suitable support at each corner of one side of the bed or other object over which the net is to be spread, so as to swing to and from the line between said corners and reach across to the opposite side of the bed, the free ends of which arms are connected with an extensible bar reaching along the front side of the bed from arm to arm when said arms are swung across the bed, and folding together with said arms when they are swung back to the line of the side of the bed on which they are pivoted, on which arms and a bar stretching between the pivots of the arms at the back the net is hung to be spread over the bed or folded back out of the way, as required, as hereinafter fully described.

Reference is to be had to the accompanying drawings, forming part of this specification, in which similar letters of reference indicate corresponding parts in both figures.

Figure 1 is a perspective view of the net spread over the bed on a frame constructed according to my invention, and Fig. 2 is a plan of the frame.

At each of the corners *a* of one side of the bed there is a rod, *b*, extended above the bedstead to a suitable height for supporting the net *c*, said posts either being pivoted so as to turn on their vertical axis, or having pivots *e* on them for the support of horizontal arms *d*, so that they may swing across the bed, as represented in Fig. 1, or back along the bar *f*, connecting the top of the posts. The ends *g*

of arms *d* are connected by an extensible bar, *h*, which assumes the position represented in Fig. 1 when the arms are swung across the bed, and forms a support between ends *g*, parallel to bar *f*, for the support of the net at the 45 front, and when said arms swing back to the bar *f* the bar *h* shortens, as indicated in Fig. 2, so as to fold together and alongside of bar *f*, so as to fold the net back out of the way when required.

The extensible bar may consist of a tubular middle section with end sections connected to the arms *d*, respectively, and sliding in and out of the tube; but I do not limit myself to any particular construction of said extensible bar.

I am aware that it is not new in net-supports to use socket-pieces with inclosed springs and supporting-stems, or parallel bars with double-jointed end arms and standard to form a folding frame, or a rectangular frame supporting brackets and angular screw-hooks, in combination with uprights carrying at their upper ends screw eyes or rings, or to use a quilting-frame with legs made in two parts telescoping together and connecting two-part end pieces; but

What I do claim as new and of my invention is—

The combination of two side posts, *b* *b*, having pivots *e* *e*, the horizontal arms *d* *d*, working on said pivots, the bar *f*, connecting the tops of said posts, and the extensible bar *h*, connecting the arm ends *g*, the whole adapted to be used on a bedstead, as described.

THOMAS A. WATSON.
